UNITED STATES PATENT OFFICE.

EPHRAIM S. JOHNSON, JR., OF NEW YORK, N. Y.

DESIGN FOR A PEN-HOLDER.

SPECIFICATION forming part of Design No. 20,215, dated October 21, 1890.

Application filed September 25, 1890. Serial No. 366,138. Term of patent 7 years.

To all whom it may concern:

Be it known that I, EPHRAIM S. JOHNSON, Jr., of the city, county, and State of New York, have invented and produced a new and 5 original Design for Pen-Holders, of which the following is a specification, reference being had to the accompanying drawing.

My design relates to that end of the pen-holder which receives and holds the pen; and 10 it consists in the ornamental configuration thereof hereinafter described.

The rod or barrel A of the holder is poly-lateral in appearance. At one extremity of 15 said rod or barrel appear, first, a circular band B; second, and adjacent to said band, a

rounded fillet C, upon the surface of which appears a raised or indented ornamental configuration; third, and adjacent to the fillet C, a plain rounded fillet D, having one side, as E, more inclined than the other. 20

An ornamental marking, substantially as indicated in the drawing, may appear on the surface of the barrel A.

I claim—

The design for a pen-holder, substantially 25 as herein shown and described.

EPHRAIM S. JOHNSON, JR.
